UNITED STATES PATENT OFFICE.

CHARLES C. HOYT, OF BROOKLINE, MASSACHUSETTS.

SHOE.

SPECIFICATION forming part of Letters Patent No. 728,235, dated May 19, 1903.

Application filed May 29, 1902. Serial No. 109,441. (No model.)

To all whom it may concern:

Be it known that I, CHARLES C. HOYT, a citizen of the United States, residing at Brookline, in the county of Norfolk and State of Massachusetts, have invented an Improvement in Shoes, of which the following description, in connection with the accompanying drawings, is a specification, like letters on the drawings representing like parts.

10 In the manufacture of boots and shoes the heel counter or stiffener, of molded leather, is arranged between the quarter and shoe-lining, with both of which it is lasted in. In the wear of shoes having the heel counter or 15 stiffener thus arranged I have observed that the shoe-lining, commonly of cotton drill or duck, is very apt to rot and break away in the vicinity of the heel long before the same lining gives way in other parts of the shoe. 20 My investigation to determine, if possible, the cause of this leads me to believe that the early rotting and breaking away of the lining at the heel, above referred to, is due largely to the heat or perspiration from the 25 foot combining with the tannic acid or other element in the counter, and, perhaps, with the paste used when inserting the counter, in a manner to cause the interposed lining, through which, of course, the combined action takes 30 place, to become quickly rotted and thereafter easily broken. My invention aims to prevent this combined action by interposing between the heel-counter and the shoe-lining a protecting member, preferably a paraffined 35 or other moisture-proof fabric. By preventing or tending to prevent the moisture from the foot reaching the counter the action referred to is, of course, prevented or reduced and the life of the cotton lining prolonged, 40 with consequent increase of wear in the shoe. The presence of this additional fabric member between the shoe-lining and counter also serves as a cushion at the sides of the heel of the wearer, rendering the shoe more comfortable 45 when upon the foot and protecting the lining against wear such as ordinarily results from direct contact with rough inner face of the counter.

In the accompanying drawings, Figure 1, in 50 perspective, shows a shoe made in accordance with my invention, a portion of the shoe at the heel thereof being broken away to better

illustrate the construction to be described; and Fig. 2 is a horizontal sectional detail through the heel portion of the shoe just 55 above the heel thereof, showing the interposed protection member.

Referring to the drawings, particularly to Fig. 1, the shoe, comprising the upper *a*, vamp *b*, sole *c*, and heel *d*, is and may be of usual materials and construction, so far as my present invention is concerned. At the heel of the shoe where broken away, Fig. 1, I have shown the usual heel counter or stiffener *e*, shown as and preferably of molded leather and inserted between the quarters and the usual shoe-lining *f*, said counter being lasted in over the heel with the lining and quarters in usual manner, or otherwise inserted, as may be desired, in the otherwise preferred construction 70 of the shoe. In accordance with my invention there is interposed between the shoe-lining *f* and the inner face of the counter *e* a protection member *g*, preferably of paraffined or waterproof fabric or other substance that 75 will prevent or resist such combination of the moisture from the foot with the tannic acid or other element or elements of the counter or paste thereon from combining to the detriment of the interposed shoe-lining *f*. 80 This protection member *g* may be of desired shape and introduced in any desired manner. I find it convenient to use a protection member of the general shape of the counter, as herein shown, though slightly larger than the 85 counter, and the same at its edges may be cemented or preferably stitched, as at *g'*, to the shoe-lining—as, for instance, during vamp- 90 ing, where the vamp-stitches include also the shoe-lining. When the counter is inserted prior to lasting, its inner face may be coated with a paste or cementitious substance which will cause the protection member to adhere closely to it throughout, thus to enable it to be lasted more smoothly and also 95 to preserve it against possible wrinkling when the shoe is in use. This protection member may likewise be included in the line or course of vamp-stitches. Of course as an alternative construction this protection member 100 may be primarily secured or cemented to the inner face of the counter and applied therewithout securing its edges to the shoe-lining. In any event, as will appear from

Fig. 2, the presence of the protection member *g* between the counter and shoe-lining effectually prevents or tends to prevent the injurious combination and action referred to, 5 and in addition thereto furnishes a cushion-wall about the heel of the shoe, which renders the latter more comfortable to the wearer and also a protection for the lining against the wear due to the rough inner face of 10 the counter. This protection member by its protecting edge also serves as a support for the counter and aids in preventing the skived upper edge thereof from curling inward, as it is apt to do when permitted to dry after 15 being heated and dampened by use.

My invention is not restricted to the particular embodiment thereof herein disclosed, but may be varied within the spirit and scope of my invention.

20 I claim—

1. A boot or shoe comprising a quarter or quarters, a lining, a heel-counter arranged between said quarter or quarters and said

lining, and a protection member interposed between said counter and lining and having 25 a counter-supporting edge extending beyond the upper edge of said counter, and between said quarter or quarters and lining.

2. A boot or shoe comprising a quarter or quarters, a lining, a heel-counter arranged 30 between said quarter or quarters and said lining, and a protection member interposed between said counter and lining and having a counter-supporting edge extending beyond the upper edge of said counter, and between 35 the said quarter or quarters and lining, and secured at its said supporting edge independently of said counter.

In testimony whereof I have signed my name to this specification in the presence of 40 two subscribing witnesses.

CHARLES C. HOYT.
